UNITED STATES PATENT OFFICE.

FRANK A. HENKLE, OF POMONA, CALIFORNIA.

SPARK PLUG.

1,425,476.

Specification of Letters Patent. Patented Aug. 8, 1922.

Application filed August 3, 1920. Serial No. 400,928.

To all whom it may concern:

Be it known that I, FRANK A. HENKLE, a citizen of the United States, residing at Pomona, in the county of Los Angeles and 5 State of California, have invented new and useful Improvements in Spark Plugs, of which the following is a specification.

The object of my present invention is the provision of a simple and practical 10 spark plug of high efficiency and durability.

To the attainment of the foregoing the invention consists in the improvement as hereinafter described and definitely claimed.

15 In the accompanying drawings, hereby made a part hereof:—

Figure 1 is a diametrical section of a spark plug constructed in accordance with my invention.

20 Figure 2 is an elevation of the inner end of the plug.

Figures 3, 4, 5, 6, 7, and 8 are views similar to Figure 2 and showing modifications hereinafter explicitly referred to.

25 Similar numerals designate corresponding parts in Figures 1 and 2 to which reference will first be had.

Among other elements my spark plug comprises a metallic bushing 1, threaded at 30 2 for connection to the cylinder of an internal combustion engine and having an interior abutment 3 as well as a socket 4 in its outer end, interiorly threaded at 5.

The inner portion of the bushing 1 is 35 chambered as shown.

35 The spark plug also comprises a dielectric member 6 having in its inner end a chamber 7 and also having abutments 8 and 9 and a longitudinal central bore 10. The dielectric member 6 is arranged in the bushing 1 and is secured in position by the nut 11; gaskets 12 and 13 being interposed between the member 6 and the bushing 1 and between the nut 11 and the abutments in the bushing 1 and on the member 6, respectively, as shown. The main electrode 14 which extends through the bore 10 of the member 6 is provided in the chamber 7 with an enlargement 15, on which is arranged a gasket 16. All of the gaskets referred 45 to are preferably of fireproof material, and they serve effectively in preventing leakage through the plug. Mounted on the outer threaded portion of the main electrode 14 are the usual nuts 17 and 18. The elements thus far described are not of my invention, though I prefer to use the construc-

tion made up to these elements because of its practical utility.

In furtherance of my invention the main electrode 14 is arranged with its inner end 60 substantially flush with the inner end of the bushing 1, and on the said inner end of the main electrode are steel bristles 19, electrically connected with the main electrode and having their outer ends separated 65 by an annular space from the adjacent portion of the bushing 1.

By virtue of the provision of the steel bristles 19 arranged as set forth, it will be manifest that on the suction stroke of 70 an engine the brush formed by the bristles will be flexed inwardly to a slight extent, and on the compression stroke explosive mixture will be compressed through and past the bristles 19 and into the inner portion 75 of the plug as shown in a chamber opposed to the bristles. The effect of this is to clear and keep clear the gap or the annular space between the steel bristle brush and the inner end of the bushing 1.

80 From this it follows that when current is supplied to the main electrode 14 sparks will jump from the ends of the bristles 19 to the adjacent end of the ground bushing 1. Manifestly the explosion will be 85 attended by jarring of the bristles sufficiently to displace any dry soot or oil that may have accumulated thereon incident to the suction or compression strokes. It will also be apparent in this connection that 90 when the explosive mixture compressed in the chamber in the inner portion of the bushing 1 is exploded any soot collected on the face of the walls of the plug will be thoroughly burned by reason of the brush constructed of the bristles 19 forming a deflector, calculated to spread the flame and direct the same against the wall of the plug. It will be further noted that 95 any carbon that may collect at the inner end of the bushing 1 will be burned off by the 100 sparks jumping from the terminals of the bristles 19 to the said end of the bushing 1.

In the modification shown in Figure 3 the bristles 19^a are carried by the inner end of the bushing 1^a and are grouped about and 105 separated by an annular space from the main electrode 14^a.

In the modification shown in Figure 4 two groups of bristles 19^b and 19^c are employed in separated relation; the bristles 110 19^b being carried by the main electrode 14^b, and the bristles 19^c being carried by the

bushing 1^b and being separated by an annular space from the bristles 19^b.

In the modification shown in Figure 5 a bunch or bunches of bristles 19^d are carried on the bushing 1^c, and a complementary bunch or bunches of bristles 19^e are carried on the main electrode 14^c.

In the modification shown in Figure 6 a bunch of bristles 19^f carried by the main electrode are arranged with their outer ends in spaced relation to the inner end of the bushing 1^f.

In the modification shown in Figure 7 a head 14^g is carried at the inner end of the main electrode and is provided with an arcuate face 14^h opposed to and separated from an arcuate series of bristles 19^g electrically connected with the bushing 1^g.

In the modification shown in Figure 8 a T-head 16ⁱ is opposed to and spaced from bristles 19^j electrically connected with a bushing of ground electrode 1ⁱ.

Manifestly all of the modifications shown and described fall within the purview of my broad invention which consists in the provision of steel bristles between the main electrode and the bushing or ground electrode at the inner end of a chamber provided in the inner portion of the bushing or ground electrode.

Having described my invention, what I

claim and desire to secure by Letters Patent, is:—

1. The combination in a spark plug, of a metallic bushing chambered at its inner end, a main electrode extending through and insulated from said bushing, and steel bristles disposed in a plane extending at right angles to the length of the bushing and main electrode, interposed between said bushing and electrode at the mouth of the chamber and carried by one of said elements and separated by a gap bordered by free bristle ends all in the same plane from the other element. 45

2. A spark plug comprising a metallic bushing chambered at its inner end, a dielectric member disposed in the bushing and having a longitudinal central bore, a main electrode extending through the bore of the dielectric member and resting in the chamber of the metallic bushing, and bristles interposed between the inner portions of the main electrode and the bushing and disposed in a plane extending at right angles to the length thereof and carried by one of said members and separated by a gap bordered by free bristle ends all in the same plane from the other of said members. 50

In testimony whereof I affix my signature. 55

FRANK A. HENKLE.
